UNITED STATES PATENT OFFICE.

WILLIAM FETZER, OF MIDDLETOWN, OHIO.

SEED-CUP FOR PLANTERS.

No. 827,003.

Specification of Letters Patent.

Patented July 24, 1906.

Application filed May 23, 1906. Serial No. 318,340.

To all whom it may concern:

Be it known that I, WILLIAM FETZER, a citizen of the United States, residing at Middletown, in the county of Butler and State of Ohio, have invented certain new and useful Improvements in Seed-Cups for Planters, of which the following is a specification, reference being had therein to the accompanying drawings.

This invention relates to improvements in feeding devices adapted for use with planters for corn, potatoes, onions, and the like, and more particularly to feeding devices employing an endless chain of feed-cups.

The object of the present invention is the provision of a plain belt, to which can be readily secured feed-cups fashioned for use with various kinds of seed, whereby the same planter may be used for planting a great variety of seed.

A further object of the present invention is the provision of a seed-cup of this character which is so fashioned that it will pick up and retain but a single seed during its passage through the hopper.

A further object of the invention is the provision of a seed-cup of this character which can be readily attached to or detached from the feed-chain.

Other objects of the invention will be apparent from the detailed description herein-after when read in connection with the accompanying drawings, forming a part hereof, wherein a preferable embodiment of my invention is shown and wherein like letters of reference refer to similar parts in the several views.

In the drawings, Figure 1 is a perspective view of a section of a feed-chain having one of my improved seed-cups secured thereto. Fig. 2 is a perspective view of the cup shown in Fig. 1 with the parts thereof separated. Fig. 3 is a perspective view of a modified form of seed-cup designed particularly for potato-planters. Fig. 4 is a perspective view of a modified form of cup designed particularly for corn-planters.

Referring now more particularly to the drawings, A designates a feed-chain which is provided with the links a, which may be of any suitable construction. The seed-cups are formed in two sections B and B', each of which is provided with substantially vertical inner walls b', which are designed to abut when the sections are assembled and which are provided with the rearwardly-extending

diverging extensions b², in which are formed vertically-disposed grooves b³, which are designed to engage the outer edges of the chain-links when the cups are secured thereto. The upper portions of the vertical walls b' of the sections are provided with recessed portions b therein, which when the sections are assembled coöperate to form a cup-shaped recess or pocket of a size to receive a single seed. It will of course be understood that the size of the cup-shaped pocket will be varied according to the particular seed for which the cup is intended. Directly in rear of the recessed portion b each section is provided with an upwardly-extending portion b⁴, which when the sections are assembled form a hump having diverging side portions, which is positioned directly in rear of the cup-shaped recess. This hump being positioned directly in rear of the cup-shaped recess prevents the accumulation of more than one seed therein during the travel of the cup through the hopper and also prevents the seed from being forced rearwardly and into the feed-chain, and thus becoming injured.

The sections B and B', forming the cup, are clamped to the links of the chain A by means of bolts C, which pass through alined apertures in the vertical walls b' thereof, and the inner faces of said vertical walls are provided with portions adapted to interlock when the sections are assembled to prevent relative movement thereof. In the form shown in the drawings these portions comprise ribs b⁵, which are formed on the wall b' of one section and are adapted to fit in grooves b⁶, formed in the wall b' of the other section when the sections are assembled. Each of the sections is formed with two or more of the ribs b⁵ and grooves b⁶, which are disposed at an angle to each other, so that when the sections are assembled relative movement thereof will be prevented in any direction.

In Fig. 3 of the drawings I have shown a cup which is particularly advantageous for use with a potato-planter. In this form the sections are provided with the vertical inner walls and with substantially flat top portions, which when the sections are assembled form a flat base. The flat top portions of the sections are provided with prongs b⁷, extending upwardly therefrom, which serve to grasp a potato-seed while the cup is passing through the hopper and hold the same centrally there-between on the flat base of the cup.

In Fig. 4 of the drawings I have shown a

cup which is designed for use in planting corn. In this form the sections are provided with depressions therein, which form when the sections are assembled a substantially circular pocket having a flat bottom, said pocket being of a size to seize and retain a single seed only.

From the above construction it will be obvious that the cups can be quickly and easily secured to any part of the feed-chain to regulate the intervals between planting and that they can be readily detached therefrom in the event of their becoming broken when it is desired to utilize a cup for planting a different kind of seed.

While I have disclosed the sectional seed-cup provided with the hump for the purposes hereinbefore mentioned, it will be obvious that said hump may be also used in conjunction with seed-cups formed in a single piece.

I do not desire to limit myself to the precise form and construction shown in the drawings, as it is obvious that many minor changes may be made thereto without departing from the spirit of the invention.

I claim—

1. In combination with a feeding-belt, a seed-cup comprising separable sections, means for clamping said sections together and clamping the assembled sections to the belt, said cup having an unobstructed seed-receiving portion when the sections are assembled.

2. In combination with a feeding-belt, a sectional seed-cup detachably secured thereto, said seed-cup having an unobstructed seed-receiving portion therein when the sections thereof are assembled.

3. In combination with a feeding-belt, a seed-cup comprising separable sections having portions adapted to engage the opposite edges of said belt, and means for clamping said sections to said belt, said seed-cups having an unobstructed seed-receiving portion therein when the sections thereof are assembled.

4. In combination with a feeding-belt, a seed-cup comprising separable sections grooved to receive the edges of said belt, and means for clamping said sections to said belt.

5. In combination with a feeding-belt, a seed-cup comprising separable sections provided with rearwardly-extending portions grooved on their inner faces to receive the opposite edges of the belt, and means for clamping said section to the belt.

6. A seed-cup comprising separable sections, means for clamping said sections together, and means for preventing relative movement of said sections.

7. A seed-cup comprising separable sections, and means for clamping said sections together, the adjacent portions of said sections being provided with interlocking portions.

8. A seed-cup comprising separable sections and means for clamping the sections together, the adjacent faces of said sections being provided with interlocking ribs and grooves.

9. A seed-cup comprising separable sections, and means for clamping the sections together, the adjacent faces of said sections being provided with a plurality of angularly-disposed interlocking portions.

10. A seed-cup comprising separable sections, and means for clamping the sections together, the adjacent faces of said sections being provided with angularly-disposed interlocking ribs and grooves.

11. A seed-cup comprising separable sections, and means for clamping said sections together, each of said sections being provided with a rearwardly-extending portion grooved to receive the edge of a belt.

12. A seed-cup comprising separable sections, each having a depression therein adapted to coöperate when the sections are assembled to form a pocket for the reception of a seed, and means for clamping the sections together.

13. A seed-cup comprising separable sections having depressions formed therein adapted to coöperate to form a pocket when the sections are assembled and portions adapted to engage the edge of a belt, and means for clamping said sections together.

14. A seed-cup having a pocket formed therein for the reception of a seed and a hump arranged in rear of said pocket.

15. A seed-cup having a pocket therein for the reception of a seed and an upwardly-extending portion having diverging side portions arranged in rear of said pocket.

16. In combination with a feed-chain, a seed-cup secured thereto and having a pocket therein for the reception of a seed, and a hump positioned in rear of said pocket and in advance of the feed-chain.

17. A seed-cup having a seed-receiving portion and a hump adjacent thereto.

18. A seed-cup having a depression formed therein constituting a pocket for the reception of a seed, and a hump adjacent thereto.

19. In a seeding device, a link feed-chain, a plurality of seed-cups, and means for detachably securing said seed-cups to the links of said chain.

20. In a seeding device, a feeding-belt, seed-cups adapted for fastening thereto, such seed-cups having pockets of a size and form to receive a single seed only.

In testimony whereof I affix my signature in presence of two witnesses.

WILLIAM FETZER.
